Robert Appel, New York, N. Y.

Application September 23, 1943, Serial No. 111,194

Term of patent 14 years

(Cl. D87—3)

To all whom it may concern:

Be it known that I, Robert Appel, a citizen of the United States and residing at New York city, in the county and State of New York, have invented a new, original, and ornamental Design for an Articulated Fabric or Similar Article, of which the following is a specification, reference being had to the accompanying drawing, forming part thereof.

Fig. 1 is a plan view of an articulated fabric or similar article, showing my new design.

Fig. 2 is a side view thereof.

Fig. 3 is an end view thereof.

I claim:

The ornamental design for an articulated fabric or similar article, substantially as shown.

ROBERT APPEL.
